UNITED STATES PATENT OFFICE.

JEROME LEWINSON, OF NEW YORK, N. Y.

TOY FIGURE.

1,314,676.

Specification of Letters Patent. Patented Sept. 2, 1919.

Application filed December 16, 1918. Serial No. 266,947.

To all whom it may concern:

Be it known that I, JEROME LEWINSON, a citizen of the United States, residing at New York city, in the county of New York and 5 State of New York, have invented certain new and useful Improvements in Toy Figures, of which the following is a specification.

My invention relates to a base for jointed 10 toy figures and it is my object to produce a base stand which will be cheap, light and jointed to the figure in such a way that the figure may be put into various life-like positions.

15 In the drawing Figure 1 is a view of a toy soldier embodying my invention, Fig. 2 a sectional view of the base stand and joint, and Fig. 3 a perspective view of the base stand.

20 My base stand comprises a flat piece of sheet metal 1 with an integral lug 2 struck up at right angles therefrom in simulation of a foot as far as the first, or ankle joint. The leg 3 is movably joined to the struck up

foot lug by a rivet 4. The several members 25 of the figure 5 are joined together by like rivets so that the members may be placed in various life-like attitudes.

As shown in Fig. 1 the soldier may be put into a kneeling position by reason of the 30 joint between the foot lug and leg while the whole figure remains upright due to the base stand 1.

By the use of my invention no extra piece of metal or soldering is required and the 35 stand may be easily and cheaply struck up from sheet metal in a single operation.

I claim:—

A toy figure comprising several members 40 movably joined together and a flat base plate provided with an integral struck-up lug at 45 right angles thereto said lug forming one of the elements of the figure and also forming a pivoting lug, said lug being movably joined to the figure members.

In testimony whereof I have affixed my signature.

JEROME LEWINSON.
